(57) **CLAIM**

The ornamental design for a swimming ring as shown and described.

DESCRIPTION

FIG. 1 is a front, left and top perspective view of a swimming ring, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a fastener.

FIG. 10 is a partial enlarged view of an area labeled 10 in FIG. 1 comprising buckles; and,

FIG. 11 is a partial enlarged view of an area labeled 11 in FIG. 2 comprising a buckle.

The broken lines shown in the drawings are included for the purpose of illustrating portions of the swimming ring that form no part of the claimed design. In addition, the dot-dash broken lines in the drawings illustrate an enlarged portion of the design.

1 Claim, 11 Drawing Sheets
